(57) **CLAIM**

The ornamental design for a plate with tread pattern, as shown.

DESCRIPTION

FIG. 1 is a perspective view showing a plate with tread pattern embodying the new design;

FIG. 2 is a bottom plan view thereof;

FIG. 3 is a top plan view thereof;

FIG. 4 is a left side elevational view thereof;

FIG. 5 is a right side elevational view thereof; and,

FIG. 6 is a front elevational view thereof.

The dot-dash-dot broken line perimeter surrounding the plate with tread pattern depicts the boundaries of the claimed design and forms no part of the claimed design. The evenly spaced broken lines depict portions of the plate with tread pattern that form no part of the claimed design.
